UNITED STATES PATENT OFFICE.

GABRIEL M. KAPRIELIAN, OF FRESNO, CALIFORNIA.

WARDROBE SUITCASE.

Application filed August 20, 1924. Serial No. 733,107.

To all whom it may concern:

Be it known that I, GABRIEL M. KAPRIELIAN, a citizen of the United States, residing at Fresno, county of Fresno, State of California, have invented certain new and useful Improvements in Wardrobe Suit-cases; and I do declare the following to be a full, clear, and exact description of the same, reference being had to the accompanying drawings and to the characters of reference marked thereon, which form a part of this application.

This invention relates to improvements in travelling bags and particularly to suit-cases.

The object of the invention is to produce a suit-case which when in folded position is substantially of the dimensions of the average suit-case which can be readily picked up and carried in the ordinary way, but which when opened is extensible to such a degree as to enable a suit coat and trousers, dresses or other similar wearing apparel to be suspended therein in such an extended position as to allow the same to be so flattened out and protected as to prevent undue wrinkling thereof.

A further object is to provide the suit-case so that several suits or dresses may be so suspended in extended position therein, whereby the suit-case when opened may be hung on a hook or other support and used as a temporary wardrobe for the articles contained therein.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a perspective view of my improved suit-case showing the same partly open to show how the extension instrumentality functions.

Fig. 2 is a plan view of the suit-case in open position and showing the garment supports and clamping elements therein.

Fig. 3 is a sectional view taken on a line 3—3 of Fig. 2.

Fig. 4 is a perspective view of one of the clamping elements.

Fig. 5 is a perspective view of the garment hanger used in connection with my improved suit-case.

Referring now more particularly to the characters of reference on the drawings, the numerals 1 and 2 designate the usual two halves of a suit-case of common design. Instead of having these two halves hinged to break along the connecting line between them, as is usual in present suit-case construction, I provide a rigid bottom board or member 3 common to both halves of the suit-case 1 and 2 and connected and hinged to the outer end of each as at 4 and 5 respectively. Flat metal bars 6 form rigid braces at each end of the bottom board 3 and the hinge connections 4 and 5 are made between these bars 6 and corresponding bars 7 and 8 secured to the sides of the halves 1 and 2 respectively. Cross-bars 9 and 10 connect opposite ends of the bars 7 and similar cross-bars 11 and 12 connect opposite ends of the bars 8. Intermediate bars 13 extend between the bars 9 and 10 at a slight spaced distance from one of the bars 7 and a similar intermediate bar 14 extends from the bars 11 and 12 parallel to the bars 8. On the bar 13 and one of the bars 7 are upstanding guide members 15, while on the bar 14 and one of the bars 8 are similar upstanding guides 16.

The members 17 and 18 are flat clamping or presser elements of any suitable design and of a width equal to the height of the members 1 and 2. On the ends of these elements 17 and 18 are combined slide members and pinch clamps 19 and 20 respectively adapted to be engaged with the guides 15 so as to position the clamping elements 17 and 18 at definite positions within the members 1 and 2 for a purpose as will presently appear, while allowing of vertical movement of said elements relative to the guides and preventing transverse displacement thereof in the suit-case.

On the inner edges of the members 17 and 18 are hinged a plurality of flat boards or flaps 21 and 22 respectively which can fold about their hinged connection with the said members 17 and 18 and with each other as the members 1 and 2 of the suit-case are moved to closed positions.

Secured to the bottom of the member 1

near the outer edge thereof is a pin 23 having a threaded base 24 on which is threaded a sleeve 25 having a top flange 26.

The numeral 27 designates a garment hanger having an open hook 28 at its upper end capable of engaging the sleeve 25 when the same is unscrewed from the threaded portion 24 and lifted over the pin 23. Hinged links 29 connect the upper free edges of the members 1 and 2 so as to hold them in horizontal position when they are extended into parallelism with the member 3.

The various brace bars, rods and other structural elements described will of course in practice be covered with suitable decorative and cushioning covering which I have not shown herein as I desire to set forth the mechanical structure of the suit-case, and such covering is a matter of decoration, 20 and convenience only and forms no important part of my invention.

In using the device, the garment to be packed in the suit-case is suspended on the hanger 28. The sleeve 25 is then unthreaded and pulled upward so that the hook 28 may be engaged therewith, whereupon the sleeve is again engaged with the threaded element 24 and the flange 26 prevents the garment hanger from coming off of the sleeve. The garment is then laid out flat across the members 1, 2 and 3 and the members 19 of the presser elements 17 and 18 are then introduced into their guides 15 and 16 and pressed firmly down against the garment to hold it in flat unwrinkled position, the members 21 and 22 of their own weight holding the part which extends across the flat portion 3 also perfectly flat and unwrinkled.

40 The hinged links 29 are then broken and the suit-case is folded to closed position with the garment held perfectly flat and unwrinkled therein. Four or five garments may be put into one suit-case and when the suit-case is opened in a hotel or other place it may be suspended by its handle upon a hook or other suspension element and the garments will then hang on the sleeve 25 ready for removal and replacement at will.

50 At the end opposite the sleeve 25 I provide a pin 30 having a plurality of weighted arms 31 swiveled thereon which may be swung out over the clamping element 18 to aid in holding the same perfectly flat against the garments.

The distance from the top of the suit-case members 1 and 2 to the inner ends of the elements 17 and 18 to which the adjacent

boards 21 and 22 respectively are hinged must be less than the height of said members, so that when the latter are folded the boards 21 and 22 may lie more or less parallel to the central part 3, with sufficient space then being had between the inner ends of the elements 17 and 18 to prevent undue pinching or compression at these points, of any clothing carried between said elements and the bottom member of the suitcase. By using two or more of each of the boards 21 and 22, they may function efficiently regardless of different total thicknesses of clothing being carried.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. In a suit-case, guides arranged therein, a flat presser element, and pinch clamps on the presser element to engage the guides and position the presser element, such presser element having a rigid flap hinged along one edge thereof.

2. A wardrobe suitcase including two side compartments open at their lower ends, a rigid bottom hinged to the outer edges of the open ends to form an extension to the length of the suitcase when open, and hinged links connecting the upper free edges of the ends of the compartments.

3. In a suitcase a projecting pin at one end thereof, a sleeve removably threaded on the pin, and an overhanging flange fixed on the top of the sleeve, whereby garment hangers having hooks may be engaged with the sleeve when the latter is threaded onto the pin and said hooks will be held against removal by the flange while permitting them freedom of movement on the sleeve below the flange.

4. In a suitcase a flat presser element arranged to press against a garment in the suit-case and movable relative to the side thereof and a flap hinged along one edge of the element.

In testimony whereof I affix my signature.
GABRIEL M. KAPRIELIAN.
